5946X

S. JONES.

Wagon Brake.

Patented May 4, 1830.

Samuel Jones,
Letters Patent Dated, May 4th 1830.

The Schedule referred to in these Letters Patent, and making part of the same, containing a description in the words of the said Samuel Jones himself of his improvements for the purpose of checking or retarding the velocity of road-waggon stages & other wheel carriages & for taking the burden off of the horses in descending a hill & for checking the waggon & taking the weight off of the horses in the ascent of a hill.

To all to whom these presents shall come: Be it known that Samuel Jones of the Borough of Bridgport in the County of Fayette & State of Pennsylvania have discovered that there was, no good method known or practised by waggoners or drivers of checking the velocity of waggon & taking the burden off the horses in descending a hill. The old method of locking the wheels with a lock chain being found to be very imperfect beside the loss of time occasioned by it in stopping to lock & again to unlock the waggon & being particularly destructive to the tire especially on turnpike roads which have of late years been so greatly multiplied in our country beside the incalculable injury thereby caused to the roads & otherwise injurious to the waggon as well as to the horses. Although a partial remedy was found a number of years ago by a contrivance by which the hind horses were somewhat relieved from the pressure of the weight by means of a friction bar which was pressed against the front part of the hind wheels by their application of a lever in the act of starting back. Yet this was found to be

Samuel Jones

considerably defective, & particularly as the hind horses have still to sustain very heavy burdens & often to go by jolts in the very unnatural position of holding back, & from which cause many very valuable horses have been ruined. To remedy which I have invented several new & useful machines or improvements for the purpose of checking or retarding the velocity of road wagons stages or other wheel carriages & for letting the burden off the horses in descending a hill & for checking the wagon & taking the weight off of the horses when resting on the account of a hill & that the following is a full & exact description of the construction & operation of some of the said machines or improvements as invented or improved by me. The said machines I call "Jones wagon lock" A friction bar for a large wagon is formed of white oak, ash or other suitable wood, about six inches wide in the middle, & 3 inches at each end by 2 to 3 inches thick & long enough to reach from one of the hind wheels to the other & to project 4 or 5 inches beyond each wheel one of its sides being straight. Near each end & opposite to each wheel when inserted on the narrowest side of the bar a piece is cut out a little wedging & dovetailed as follows. A line 6 inches long is drawn on the upper side of the bar, parallel with & one & one half inch from the edge next the wheel or straight side an other line 4 & $\frac{3}{4}$ inches long is drawn along said edge, so that a line drawn from the middle of one of these lines to the middle of the other would be at right angles with said edge, another line - similar to the first is drawn on the under side but one eighth of an inch shorter & $\frac{1}{4}$ to $\frac{1}{2}$ inch

from the lower edge, & another line corresponding with the second line is drawn along the edge at the under side also one eighth of an inch shorter, then the corresponding line to the upper edge, a line is then drawn from each end of each line on the same side of the bar, to the corresponding end of the other line. The piece thus marked out is to be sawed & cut out to the mark: this is for a narrow wheeled wagon of two inch tire for a broader wheeled wagon the notch should be cut out proportionately wider; in the place where this piece is cut out a temporary wedging & dovetailing block is to be fitted which I call the friction block & which may be 3 or 4 inches in thickness, & would stand about 4 or 5 inches above & below the bar; this temporary block may be knocked out & easily replaced when worn out; a notch made sawing & not dovetailing & a block made to fit it I believe would answer the purpose & perhaps equally as well as the other: another method of applying a temporary block is to bore 2 holes horizontally & opposite this each end of the friction bar, one on each side of the wheel, this each of which, are iron clamps, or screw bolt about $\frac{3}{4}$ of an inch in diameter & 8 or 9 inches long is to pass from the side next to the wheel, having a screw cut on this end about 5 or 6 inches & a nut made to fit it, on the end of each of these next to the wheel there should be passed two strong claws the points of which should be about an inch & a half apart & so bent as to hold the block fast when it is placed between them, & which should be far enough apart for the wheel to turn round between, without touching them; any piece of wood or other substance suitable for sustaining the friction of wheels, placed between the claws &

against the edge of the bar, or in a notch cut in the bar for the purpose, so that the clamps will have a sufficient hold, & the nuts drawn tight, may serve when drawn with sufficient force against the wheels to produce the requisite friction. A plate of cast or wrought iron, may be nailed to a temporary block of wood or held fast to it by the clamps & applied to the wheels as above to sustain the friction when it might be deemed necessary. To prevent the dovetail or wedge shaped block from splitting the friction bar the corners between the notch & the end of the bar should be shaved a little rounding to a band about one & $\frac{3}{4}$ inch wide drawn on close to the notch, & a nail driven horizontally through the bar at the other side of the block & riveted tight.

The friction bar may be varied in size & shape & made of wood or metal or part of each according to circumstances I do not claim the invention of the friction bar, nor of the staples which support it, nor the springs attached to it, but suppose them to be public property as they have been long in use in the old plan of applying the bar to the wheels by the hind horses as herein mentioned but I do claim as new & as my own invention & discovery the invention of the dovetail & wedge shaped notches in the friction bar & of the temporary blocks of wood & to be applied to the wheels of the waggon as above specified as my improvement on & substitute for the former plan of mortising the blocks into the lower side of the bar & fixing plates of iron on them to keep them from moving, which temporary blocks of wood are found to answer better than iron, but on muddy roads the

wood record rather fast the above-mentioned temporary blocks, might be plated with iron & in such case used to advantage. The friction bar when in use on a road-waggon or any other waggon or carriage to which it may be applicable, may be confined to & across the bottom of the bed, by two staples of sufficient strength & large enough to admit the bar to play back & forward in them about 6 inches. At the place where it comes in contact with the front of the hind wheels, where the staples must be fastened to the longer bed rails for the purpose, by boring holes & inserting the prongs of the staples thru them & screwing a bar on each prong or a staple may be formed with straps ranging along the under side of the lower bed rail & fastened to it by two screw bolts, with heads to each strap, passing thru the bed rail from above & thru the straps & fastened by bars below. To keep the friction bar & blocks off from the wheels when not in use, in those instances of application herein described, where no other plan is described, I make use of two springs made of steel about 15 inches long & of sufficient strength to produce the desired effect, & bent so that the bar may play 3 or 4 inches, one of these springs must be fastened to the hind part of each end of the bar so as to extend thru to the outside of the staple before mentioned. A studded nail about half an inch thick should be driven into the underside of each end of the friction bar when in its proper place both either inside or outside of the staples as guides for the bar or otherwise two artificial wheels may be made of cast or wrought iron each about 3 ft 4 inches in diameter.

5/4/1830 5946X

6

(or the distributor, might be less if the prongs of the staples were bent so that their outer extremity should be perpendicular to the outer extremity of the lower box rail,) & three-fourths of an inch thick, with a half inch hole thru the centre, 2 holes should be bored thro. the friction bar, one at each side of the wagon bed, and side of wood as near to the staples as to admit the wheels to play against those so guided; 2 pins should be made about 4 inches long & half an inch square in thickness, with a head an one end, & a slit in the other end to hold a key; one of these pins should be inserted thro. each of the said holes in the bar, from above, then thro the wheel which is to be fastened there by putting the key into the slit made to receive it.

To apply the friction bar to the purpose mentioned I have invented a variety of methods, the following are descriptions of some of them: 1st is a follower shaft is made of iron for a common road wagon about one & $\frac{1}{2}$ inch square which is to be placed as near as practicable to the coupling pole where it should be a little turned & must be parallel with & the centre of it to be about 3 inches from the front part of the hind axle, & to extend from within 4 inches of the near side of the wagon bed, or that side where the driver usually walks to about 18 $\frac{1}{2}$ inches beyond the coupling pole where it should be rounded 2 $\frac{1}{2}$ inches making a shoulder there, on this shaft at 10 inches each side of the middle of the coupling pole is fixed a roller 3 inches in diameter & $\frac{1}{2}$ inch thick, on the frustumy & back part of each of which is permanently fixed a broken staple

To these are attached a few links of chain, made & twisting, so as to lie close to the rollers & to wind on them, when the shaft is turned; to each of these chains is fixed a rod of round iron, about half an inch thick with an eye formed on each end, these two parts together constitute the connecting chain & to this again is fixed a screw bolt about 10 inches long & half an inch square, & about 4 inches of it rounded & a screw cut on it & each of which is to be inserted thro a hole bored thro the friction bar for the purpose, at right angles with the shaft & opposite to one of the rollers, & a screwing nut screwed on each of them at the fore end. The connecting chains & screw bolts, altogether are to be of such length as to admit of regulating the distance of the bar & blocks, from the wheels, & the elevation of the lever by screwing & unscrewing the nuts. The shaft is to be fixed to the hind bolted at the place aforesaid, by 2 strong eye bolts with shoulders, in which it is to turn, passing thro the holes & confined by bars screwed on them behind, one of them at the far end of the shaft where it has been rounded & the other one which should be the strongest & the shoulder turned down, close inside of the stirrup band & the shaft should be rounded from the end as far as to where it turns in the eye so that it may turn freely, on the outer end of the shaft which should again be made square with a shoulder & as large as it will admit to pass thro the eye of the screw bolt, is fixed a hand lever made of iron four feet or more in length, & fastened to its place by a pin or key or a screw & bar at the end.

To regulate the lever at the proper place, when

the necessary friction is applied I have invented a number of ways, some of which I shall here describe, a cord or strap may be fastened to the end of the lever & brought forward & wound on a wheel, with a handle, that may be attached to the forward part of the wagon & stopped at the place required by a rag wheel & click, or a chain about 2 1/2 or 3 feet long may be fastened to the lever about 3 1/2 feet from the shaft on a foot from the other end, and a hook drove into the other end of the swift piece, or to the lever bed coil to hold it in when the requisite friction is attained.

When this machine is required to be applied, if the wheel & c is used, the operator takes hold of the bar & turns it until he has applied the requisite power, when the click on the rag wheel secures it until it is wanted to be withdrawn, he then turns the click & the springs force the bar off of the wheels, or if the chain is used to confine the lever, which made I prefer, the operator takes hold of the hand lever & bears it down which to the chain on the no-runs draws the bar against the wheels, when he has applied the quantity of power which he judges necessary for the occasion, he confines the lever to its proper place, by hitching the lever chain to the hook, as aforementioned, & when the friction is to be withdrawn, he unhitches the chain & the springs pressing against the shanks of the staples, will draw the bar & block off of the wheels I believe that a wooden bar & chain might be substituted for the iron shaft & lever, by making them as strong as iron & iron as will admit to require, nothing being

with iron bands, rivets & screw bolts, where necessary; & that wooden springs to the friction bar, might be substituted for steel. —

N. 2, is in every respect the same as N. 1, except that it has but one roller, connecting chain, screw bolt &c., as described in N. 1, instead of 2 & which roller &c., should be placed directly over the coupling pole, where there is room for it, & consequently higher on the bolster, where there is not room, then as close to it as practicable, & must be applied in the same way, & the shaft may be shortened, to extend just beyond the coupling pole, where the eye for bolt., must be placed for it to turn in. N. 3, is the same machine as N. 1, & must be used in the same way, the only difference, is in the friction box, which is to be cut off in 2 places in order to accommodate it to the waggon, the point of whose bounds rest on the coupling pole & therefore cannot conveniently be fixed to give room for it to play in its integral character. In the end of each piece, where it has been cut off & which, must be previously bonded with a strong iron band, must be filed lengthwise, a strong iron pin to project an inch, on each side must be inserted into a hole bored into the bounds for that purpose, & over which hole at each side, should be nailed a plate of iron, with a corresponding hole, to prevent the wood from wear ing, & so placed that when a small block is fitted to the notch in each section of the bar, & both blocks brought in contact with the wheels, each section will be in the same with the other, & as near hor izontal as circumstances will admit, The connecting chain in this will require to be placed as

upon the outer sides of the wagon bed as practicable
A.M. As a substitute for the roller connecting chain
or chain bolt described in A.1.4 for the purpose of pushing
back the friction bar & blocks from the wheels
when not in use, instead of using the fore and such
springs on the friction bar, for that purpose, which
are little to get out of order, as well as to simplify the
construction & save expense, I have invented the fol-
lowing described eyebolt, which I shall call the shaft
eye bolt, connecting rod or chain. That the shaft, where
the rotation is to be described to be placed & which
at that place should be made a little the strongest,
a hole must be punched about one inch square,
at the forward side, & tapering to about half an inch,
at the opposite side, the shaft eye bolt should be
made with a shank, just to fit the said hole & pro-
ject thru. The shaft, about 3 fourths of an inch, which
projection should be rounded & a screw put on
it & a bar fitted to & screwed tight on it. At the for-
ward side of the shaft, the eye bolt should be 2 3/4
inches long 1 1/2 inch perpendicular with 2 3/4
of an inch thick, which consequently forms a han-
dle & which should be placed on the up-
per side. The forward corners should be rounded
& a hole full half an inch or more diameter punched
there, horizontally, at such distance as that the centre of
the hole shall be 2 3/8 inches from the centre of the
shaft, that this hole or eye must be inserted one end
of a half inch rod of round iron & an eye turned
around on it, & which with the eye of the shaft eye
is to form a joint, which should meet close but
loosely with the sweep of the base. The other end
of this connecting rod, should extend forward

the friction bar to within about an inch of the -
wedge piece, or where there is no wedge piece, far enough
to give room for the friction bar to play 11 or 5 inches
off from the wheels, so as to admit a good sized
friction block, & a screw & nut on that end of the rod,
about eleven inches or long enough to give suffi-
cient room to fix the friction bar at the requisite
distance. 2 one wire, nuts & screws on the rod, one
at each side of the bar to confine it at the place required.
A joint may be made in the connecting rod, if the
construction of the wagon should require it, about
a foot from the end of the rod, including the screw,
2 of the above mentioned holes should be made thru
each shaft, & the shaft eye bolts fastened in them
as aforesaid, when circumstances will admit if
there is sufficient room for them to play freely,
one of them on the rear side, between the stirrup
hounds & the bushes, inward, ~~upward~~, from the eye bolts, in which the shaft turns, &
the other at an equal distance from the coupling
pole on the other side, otherwise it will answer
as a general rule, to place them about 20 inches
apart or 10 inches from the middle of the cou-
pling pole. The other ends of the connecting rod
must be inserted thru the friction bar as aforesaid at
a corresponding distance, each way from the cou-
pling pole with the shaft eye bolts. The screws & nuts
on the ends of the connecting rods are intended to
regulate the distance of the friction bar from the
wheels according to the size of the friction blocks & the
opposite elevation of the cars by drawing or re-
moving the nuts. The connecting rod being stiff
when the force is exerted it pushes the bar and

The blocks off of the wheels, where it should be confined when not in use, by hitching the lower chain to a hook drove into the bed at a convenient place for the purpose. In every other respect except what is here mentioned or mentioned, it is similar to A.1. & must be worked in the same way. On a hook about $\frac{3}{4}$ of an inch diameter may be welded to the connecting rod & inserted thru. the shaft eye bolt & fastened thereto a key thru. the end of the hook, or a hook bolt may be made the shank of which shall be one inch square. to the shaft from whence thru. the shaft it should be apertly similar to that of the shaft eye bolt, just described & should be fastened to the shaft in the same way. The hook which should be $\frac{3}{4}$ of an inch diameter & the centre of which should be epunched from the centre of the shaft, should project from the other end of the shank at right angles about $\frac{3}{4}$ inches, & should be inserted through the eye of the connecting rod, just mentioned & fastened thereto a key thru. the end of the hook. A 5.00 eye screw bolt piece eighths of an inch thick is made and passed thru. the middle of the friction bar from behind with a screw cut 1 inch on the forward end & a bar made to fit it & screwed on tight & on the edge of which just behind the bar is attached about two inches of chain similar to that which is wound on the roller as described under A.1. which is again attached to an eye made on one end of a half inch rod of iron, the other end of which is extended to near the hind angle between the coupling pole & the rear hind wheel, where it passes thru. one end of a strong clevis, with an open space of 4 by $1\frac{1}{2}$ a $\frac{1}{4}$ inch & a strong round head formed on it, but so as to admit of being

party in the armrest; the other end of the armrest is to have a hole thru it three fourths of an inch diameter & to receive thru it the small end of the following screw pin, & which is fastened there by a key thru the end of the pin; the screw pin may be made from one & a half to 2 $\frac{1}{2}$ feet in length, & one inch in diameter except about 6 inches of it, which is to be $3\frac{1}{4}$ " of an inch diameter & thru the end of it which a place is punched to receive a key, a slot must be cut, about four inches on the thicker part, next to the small end and the other end flattened & shouldered to receive a crutch or handle which is to be fixed to it; An antiquation roller of cast iron must be made about 2 $\frac{1}{4}$ inches diameter, & one & a half inch thick, with a hole thru the centre, about $3\frac{1}{4}$ of an inch diameter. A strong cap of iron must be made to fit on, & across the coupling hole, & firmly nailed there, having a pin on the rear end, of a size to fit in the roller, & to rise perpendicular from the rear end of the strap; The roller must be fitted on the pin & confined by key, thru the upper end of it & must be placed as near the friction bar, at its nearest proximity, as will give sufficient room for the play of the chain on the roller & conduct the draught in a line at right angles with the friction bar. A strong plate of iron is to be firmly attached by screws or nails to that part of the hind angle, or the yoke & bolster together, or to a block fitted in between them & fastened there for the purpose, according to the construction of the wagon, at the place that will give the armrest, when fitted on the end of the shaft or screw pin above-mentioned a sweep of about 7 inches &

114

room for the hand to turn it, without touching the coupling pole, or any other part of the wagon; Then this plate, must be fastened, a female screw one inch in diameter, in a direction toward the far side of the collar, & where wood intersects, a hole must be bored thru it in the same direction & at the forward side, must also be a plate of iron with a hole thru it $3\frac{1}{4}$ of an inch in diameter in the same direction & firmly fastened there, as a guide, & support to the screw pin; To put it together the screw pin is screwed thru the screw plate, the small end first thru the other plate & then one end of the device before mentioned is fastened there with a key, and when going to use it the operator takes hold of the crank & turns it so as to withdraw the screws, which draws the friction bar with the blocks against the wheels & causes the necessary friction, & to remove them from the wheels the friction is reversed, when the springs on the bar will push them off.

116. A shaft of iron is formed, one inch square & about 31 inches long, more or less according to the middle of the wagon bed, & placed under & across the bed at right angles, just behind and at such distance from the friction bar as will be most convenient, to actuate the machine there with & give it full scope for operation & reaches from about $5\frac{1}{2}$ inches of the near side of the bed to about 1 inch beyond the coupling pole, where the end of it is rounded & placed in a strong eye bolt the shank of which passes thru the pole & is fastened by a bar turned on the end below & after a turn cut on that end of the shaft to a bar turned on it, to confine it

to its place, & near the other end it turns in a staple fastened to the under part of the lower bed rail, where it is also a little rounded, near the far end of the shaft. A pin at the middle of the pole, a pinion is formed on it having 16 teeth which are to work in a rack of cast or wrought iron about 7 inches long two inches wide & 1 1/4 inches thick having 5 half inch teeth. This rack is on the driving pole, with the teeth upward where it is confined by the said eye bolt & by a strong iron spoke driven into the pole on the opposite side of the rack from this eye bolt & by the pinion, & through the forward end of it lengthwise is a perpendicular slot about 5/8 of an inch wide & 2 inches long, then which a slot or fork, horizontally the crosswise is a hole 5/8 of an inch diameter, a round iron bolt is made 5/8 of an inch thick & about 7 inches long, having an eye 5/8 of an inch diameter formed on one end & about an inch of a screw end on the other end. The eye of this bolt being a little flattened is inserted in the fork or slot of the rack & a pin with a head on one end passed thru the holes in the rack & the eye of the bolt, & confined there by a box thru the pin. The other end of the bolt is passed thru a hole bored thru the middle of the pinion bar so as to fit tight in it & confined by a box or nut on the ends. A cog wheel 4 inches in diameter & three eighths of an inch thick is placed in the shaft, close to the waggon bed, & a click fastened to the bed to stop the shaft from turning over when required. To this click is attached a strap or cord which is passed thru a staple fixed to the waggon bed above the cog wheel & brought forward & passed thru another staple driven into

the moggan box, or into the head at a convenient place, a handle fixed to it for convenience, on the rear end of the shaft a crank may be fitted to it that the shaft should be shortened 2 or 3 inches & the machine moved further back & the bolt which connects it with the friction box proportionally lengthened, to give more scope to the crank, but as it would not be so convenient in this situation between the hind wheel & the moggan bed to turn a crank fixed to the shaft, which should produce sufficient power, I have invented a sliding - hand lever to be placed on the outer end of the shaft instead of the crank & which is made according to the following description. A rag cylinder of cast iron is formed about $4\frac{1}{4}$ inches long & 2 inches in diameter including the teeth, having an inch square hole thru the middle lengthwise, with 8 teeth or catches on its periphery running in the same direction from each end to within $\frac{1}{4}$ of an inch of the middle, leaving a space round it three $\frac{1}{4}$ of an inch wide. The teeth in each end standing in a contrary direction to those of the other & are formed as follows, one side rises from the periphery of the rag cylinder about $\frac{1}{4}$ of an inch in a direct line from the centre, whence it descends in a curve to within $\frac{1}{4}$ of an inch of the base of the next & so on all round the space between the teeth on one end, must correspond ^{with} the space between those of the other end, so that the stop may slide freely from one end of the rag cylinder to the other, the other piece of cast iron which I call a lever box, is made of a rag cylinder going in about long & $\frac{1}{2}$ inch in diameter & $\frac{1}{4}$ of an inch

thick, which slides freely toward on the ray cylinder, midway between the two ends of this bar is a longitudinal slit or groove thru the bar, containing two keys of an inch wide, the which a stop made of steel, of a size to play freely in this slit & in a narrow expanding one, made thus, the lower band, is placed & confined to its place, by a spring placed over it & fastened to the band, & bar, by a screw or rivet, which fastens them both. To the band thus connecting the bar, to which it is firmly fastened as aforesaid, a hand lever, of which it constitutes a part is attached; this hand lever is made of iron, about $\frac{3}{4}$ of an inch square, next to the band & half an inch at the other end, & the above mentioned band formed on the end of it, & may be of any convenient length from 20 inches to 3 feet is supposed to be sufficient. The ray wheel must be slid on the shaft, to its place, against the lower bar rail, then the hand lever & bar being slid on the ray cylinder, both must be slid on the shaft, next a washer large enough to prevent the bar from sliding off, must be slid on the shaft, & then all fastened there, by cutting a screw on the end of the shaft, & screwing a bar on it or by a key or join thru it. To use this machine, the operator takes hold of the handle lever, & placing it over that end of the ray cylinder which is adapted to the purpose, he raises it to a convenient height when the stop slides freely over it, then by reversing the motion the stop catches one of the teeth of the ray cylinder & he bears down the lever which turns the shaft, until it is stopped by the friction of the disk catching the ray wheel & screwing it

until he raises the lever & removes his purchase, when he bears it down as before, & thus continues until he has applied the requisite force against the wheels. When the friction is to be withdrawn from the wheels, he takes hold of the handle attached to the card as aforesaid with one hand & pulling it downward at the same time bears on the hand lever with the other until the click is loosened & raised, & lets the shaft turn back again. And to bring down the lever without turning the shaft, he slides it to the other end of the rag cylinder from whence it is brought down again, the stop sliding over the rag cylinder, when raising the lever against the stop catches the tooth, & the shaft is turned in a contrary direction from the first & the bar pushed back & such operation is renewed until both ends of the friction bar, rest against the forward prongs of the staples in which they slide & which are placed at a proper distance for the purpose.

4. A block of suitable wood, which I call the wedge block is formed 2 inches thick 12 inches long, 4 inches wide at one end & tapering to a point at the other end this is the dimensions when the space between the friction bar, with blocks five inches thick fitted in the notches & pressed against the wheels of the wagon & the waist piece is 14 inches, when the space is greater the waist must be enlarged equally at each end so as to reduce the same angle & with the wedge hereafter to be described to fill up the said space. This wedge block must be formed on a planed post

17

to the side of the lowest piece, next to the friction
bar & the widest end which is to be at right angles
with it, to reach about 12 inches beyond the camping pole,
the point at the near side; where there is no wooden
piece, a piece of wood must be firmly attached to
the wooden side of the waggon bed as a substitute
for it; Another block which I call the wedge is
formed of similar wood, & of the same dimensions
as the wedge block first described. & must be placed
so that when the two shaping sides come together
the other two sides will be parallel to each other,
consequently the widest end will be at the near
side from whence it must extend, the same
thickness & two inches wide against & to the rear end
of the friction bar which for this purpose must be
of equal width, from one end to the other, & may be
about 5 inches wide. In other respects it is similar
to that first described, & must be attached to the
waggon bed by staples &c in the same way—
This part I call the wedge stock. To this end must
be firmly riveted a piece of iron, to strike on,
to apply & to withdraw the friction, & which shall
cover the end of the stock & project about $\frac{3}{4}$ of an
inch beyond it on the forward side, & connected
with which must be 2 straps extending along
the forward & the back part of the stock, thru each
of which must be punched 2 holes for the rivets.
The wedge must be inserted thru the staple at
the near side of the waggon, in which the friction
bar slides & pushed forwards to its place as before
described, where the far end must rest on the camp-
ing pole, to which if too low must be nailed a
piece of wood to raise it on a level with the bar,

The rear and resting on the staple: A hooked nail must be driven into the under side of the wedge stock inside of the staple to keep it from slipping out. A hammer of cast or wrought iron, of a suitable weight & form with a handle of convenient length, must be prepared & may be fixed, by a cord or chain to the friction bar or the wagon bed or waist piece, with which the operator strikes on the end of the wedge stock to cause the friction against the wheels & to withdraw it, he strikes in a contrary direction against the above-mentioned projection.

What I claim as new & as my own invention or discovery in the above described machine & for which I ask an exclusive privilege, is as well the improvement of the staple & wedge reshaped notches in the friction bar & of the temporary blocks of wood &c. to be applied to the wheels of road wagons, stages &c. as herein specified & the machines or methods of applying the friction bar, with the blocks as herein described & before claimed to be my invention, under the heads of A.1.2.3. &c. all involving the same principle of the hand lever, A.5. involving the principle of the screw & crank, A.6. involving beside the hand lever & the crank, the pinion & rack, & No.7. involving the principle of the wedge, as the main general principle which is involved in all of them, of the manual application & maintenance of a certain of a sufficient regular & determinate friction against the wheels of the wagon or carriage by the means of the mechanical power.
